[57] CLAIM

The ornamental design for a "diverter hood", as shown and described.

DESCRIPTION

FIG. 1 is a perspective view of the diverter hood, showing my new design;

FIG. 2 is an enlarged right side elevation view thereof;

FIG. 3 is a front elevation thereof;

FIG. 4 is a rear elevation thereof;

FIG. 5 is a top plan view thereof; and,

FIG. 6 is a bottom plan view thereof.

The broken line showing on FIG. 1 is for illustrative purposes only and forms no part of the claimed design.
